REMOVABLE SKATE AND BLADE

Patrick Adonizio, Pittston, Pa.

Application July 18, 1939, Serial No. 285,203

2 Claims. (Cl. 280—11.17)

One object of this invention is to provide an ice skate having a tread of novel form, and another object of the invention is to provide novel means whereby one tread may be mounted, in the room of another, on a base plate which is attached to a shoe.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in side elevation, a device constructed in accordance with the invention;

Fig. 2 is a section on the line 2—2 of Fig. 1;

Fig. 3 is a section on the line 3—3 of Fig. 1;

Fig. 4 is a fragmental side elevation showing a modification;

Fig. 5 is a fragmental side elevation showing another modification.

The device forming the subject matter of this application preferably is made of metal throughout. It includes a narrow blade 1, forming part of a tread, which, as a whole, is marked by the letter T. A tubular reinforcing rail 2 is provided, and is supplied in its bottom with a slot, receiving a portion of the blade 1, the blade 1 extending upwardly to the top of the rail 2. The rail 2 and the blade 1 are joined together by welding or otherwise. The structure as thus far described is of importance, in that it enables the blade 1 to be thin and have an unusually secure hold on the ice. The structure, moreover, saves material.

At its forward end, the blade 1 has an upwardly extended and forwardly curved nose 3. The nose might be straight, as shown at 3a in Fig. 4. It might be straight as shown at 3b in Fig. 5, the blade 1b being prolonged in front of the nose 3b to form an extension 4, the reinforcing rail 2b being extended well upon the nose 4, to stiffen it. In its upper end, the nose 3 has an opening, illustrated sufficiently by the corresponding parts 5a and 5b in Figs. 4 and 5, respectively.

The numeral 6 marks an article of footwear, such as a hockey shoe. The sole of the shoe 6 has been indicated at 7 and is substantially coextensive in length with the shoe 6, and forming part of the shoe. The sole 7, may be the ordinary shoe sole, of leather of the like, if preferred.

To the sole 7, at the forward end thereof, is secured a metal reinforcing strip 8, which, preferably, is approximately coextensive in width with the sole or base 7 and is somewhat greater in length than half the length of the sole of the shoe 6. At its forward end, the strip 8 has a depending, forked stud 9, into which is inserted the upper end of the nose 3, the nose being connected to the stud removably, by a securing element 10, such as a nut and bolt. At its upper end, the stud 9 has a head 11 of liberal dimensions, making a firm and secure union between the stud and the strip 8.

The reinforcing rail 2 is received within and secured to a downwardly tapered rear post 12, having a threaded cylindrical portion 14 merging into a smooth, reduced, cylindrical neck 15, the post 12 preferably being hollow. The neck 15 is received within a collar 16, carried by a rear strip 17, attached to the sole 7. The collar 16 is externally threaded. A threaded coupling ring 18 is detachably engaged with the cylindrical portion 14 of the post 12 and with the collar 16, and abuts against the strip 17.

The post construction and associated parts 25 are duplicated, as shown at 19, in connection with a forward strip 8.

The coupling rings 18 are threaded down on the cylindrical portions 14 of the posts 12, the necks 15 are inserted into the collars 16, and the coupling rings 18 are threaded upwardly upon the collars 16, to hold the parts assembled, as in Fig. 2. This operation lines up the hole in the nose 3 with the holes in the stud 9, and the securing element 10 is mounted in place.

The structure is simple, but it affords an inexpensive and convenient means whereby one skate, or tread may be substituted in place of another, without detaching the base or sole 7 from the shoe 6.

Having thus described the invention, what is claimed is:

1. A skate including a base plate having collars, a tread having posts provided with smooth upper ends received in the collars, and coupling rings threaded on the posts and on the collars.

2. A skate including a base plate having collars, a tread having posts provided with smooth upper ends received in the collars, coupling rings threaded on the posts and on the collars, the tread having an upstanding nose, and the base plate being provided with a part wherewith the nose coacts, said part and the nose having registering openings, the openings being brought into registration when the rings are threaded on the collars, and a securing element detachably mounted in the registering openings.
